UNITED STATES PATENT OFFICE.

LOUIS E. JUNG, OF NEW ORLEANS, LOUISIANA.

DESIGN FOR A BASKET.

No. 37,662.

Specification for Design.

Patented Nov. 14, 1905.

Application filed September 15, 1905. Serial No. 278,677. Term of patent 7 years.

To all whom it may concern:

Be it known that I, LOUIS E. JUNG, a citizen of the United States, residing at New Orleans, in the parish of Orleans and State of Louisiana, have invented a new, original, and ornamental Design for Baskets, of which the following is a specification.

Referring to the drawing forming part of the specification, the figure is a perspective view of a basket, showing my new design.

I claim—
The ornamental design for a basket, as shown.

LOUIS E. JUNG.
